UNITED STATES PATENT OFFICE

100,784

DESIGN FOR A SHOE OR SIMILAR ARTICLE

Helen Kozak, Hollis, N. Y.

Application June 4, 1936, Serial No. 63,014

Term of patent 3½ years

To all whom it may concern:

Be it known that I, Helen Kozak, a citizen of the United States, residing in Hollis, in Queens County, in the State of New York, have invented a new, original, and ornamental Design for a Shoe or Similar Article, of which the following is a specification, reference being had to the accompanying drawing, forming part thereof:

Figure 1 is a plan view of a shoe showing my new design.

Figure 2 is a side elevation of the shoe, partly in perspective.

The dominant feature of the present design

resides in the ornamental effect obtained in a shoe by the combination of a strap of contrasting material across the toe of the shoe and curved upwardly at the center, a second strap across the instep buttoned at each end, and the upper having a pair of openings directed downwardly from said second strap and intermediate the ends thereof.

I claim:

The ornamental design for a shoe or similar article, substantially as shown and described.

HELEN KOZAK.
